POCKET FILE CASE

William H. Stefanakis, Long Beach, N. Y.

Application October 27, 1951, Serial No. 17,141

Term of patent 14 years

(Cl. D86—10)

To all whom it may concern:

Be it known that William H. Stefanakis, a citizen of the United States of America, residing at Long Beach, in the county of Nassau and State of New York, has invented a new, original, and ornamental Design for a Pocket File Case, of which the following is a specification, reference being had to the accompanying drawing, forming part thereof.

Figure 1 is a plan view of a pocket file case, embodying my new design.

Figure 2 is a side view thereof.

Figure 3 is a cross-sectional view taken on the line 3—3 of Figure 1.

The case has marginal stitching at both side edges meeting at the left pointed end of the case while at the right end, both lines of stitching turn inwardly and forwardly to form small loops spaced apart. In addition, a further short pair of lines of stitching extend from the marginal stitching inward from the forward portion of the case part way toward the midline of the

latter and then turn forward at obtuse angles to the meeting point of the first mentioned lines of marginal stitching to terminate in a sharp point within the point formed by the marginal stitching.

I claim:

The ornamental design for a pocket file case, as shown and described.

WILLIAM H. STEFANAKIS.
